UNITED STATES PATENT OFFICE.

WILBUR B. TIMBERLAKE, OF JACKSON, MICHIGAN.

RACK FOR DISPLAY-CARDS.

1,260,095.

Specification of Letters Patent. Patented Mar. 19, 1918.

Application filed October 3, 1914. Serial No. 864,803.

To all whom it may concern:

Be it known that I, WILBUR B. TIMBERLAKE, a citizen of the United States, residing at Jackson, in the county of Jackson 5 and State of Michigan, have invented certain new and useful Improvements in Racks for Display-Cards, of which the following is a specification.

My invention relates to racks for holding 10 display cards, and has for its object to produce an improved rack of this kind formed entirely, or mainly, of wire, and constructed to support the card securely, and so that it shall be held against any tendency to curl 15 or otherwise become distorted in shape. As the invention is capable of being embodied in various forms, I have, in the accompanying drawings, illustrated six forms thereof, Figure 1 being a perspective view of one 20 form of the invention; Fig. 2 a perspective view of another form of the invention; Fig. 3 a perspective view of a third form of the invention, the standard being broken and the base omitted; Fig. 4 a perspective view 25 of a fourth form of the invention the standard being broken and the base omitted; Fig. 5 a perspective view of a fifth form of the invention the standard being broken and the base omitted; and Fig. 6 a perspective view 30 of a sixth form of the invention, the standard being broken and the base omitted.

In each form of my invention the rack consists of a base, a standard rising therefrom, and a card frame, quadrilateral in general 35 outline, carried by the standard. In many instances preferably but a single piece of wire enters into the formation of each rack, this being so shaped as to completely form the several parts. The base is of a shape 40 and size to afford a firm support for the article. As represented in Figs. 1 and 2 of the drawings, it is rectangular in outline, though other shapes might be adopted, and from this rises the standard. In the form 45 of invention shown in Fig. 1 the standard B rises from one side or edge of the base A, while in Fig. 2 the standard B' is represented as rising from the center of the base A'. Each form has advantages, that represented in Fig. 1 permitting the standard 50 and the card it carries to be in advance of the base, while that shown in Fig. 2 affords a better support.

The card-supporting frame is at the upper 55 end of the standard, being preferably

formed, as stated, either in whole or in part, from the same piece of wire as that employed in the construction of the base and standard. It will be seen by reference to the drawings, that in each form of the invention 60 the lower edge of the card rests upon a support or supports, and that it is protected all around, that is near each of its four edges, each edge being protected on one side at least, and in some forms of the rack on both 65 sides. Such a frame holds the card securely and flat, preventing it from curling, warping or twisting out of shape.

In the form of rack illustrated in Fig. 1 the card frame c consists of a lower horizontal bar 2, an upper horizontal bar 3, and two side bars 4, 4. The side bars are connected respectively, with the upper and lower bars by horizontal loops 5 that preferably extend forward, bringing the side bars in advance of the horizontal bars. The lower horizontal bar consists of two members that spring from the standard B so that the card frame is centrally disposed with reference thereto. In order to support the card and hold it from falling when placed in the frame, a spring clip 6 is secured to the lower bar 2, preferably at the junction thereof with the standard. The loops 5 extend around the side edges of the card and prevent its lateral movement. The quadrilateral, rectangular frame formed by the bars 2, 3 and 4, 4, engages with the card all around, near each of its four edges, the upper and lower bars being behind the card, 90 and the upright bars in front thereof. As represented in the drawings, the card is attractively exposed and supported, is securely held and prevented from warping.

The card frame C' represented in Fig. 2 95 differs from that shown in Fig. 1 in that a second pair of upright bars 7, 7, are employed. These are preferably parallel with and just back of the bars 4, 4, and directly connect the horizontal bars inside the loops 100 5. The bars 7 are secured to the bars 2 and 3 by brazing or by any other suitable method of connection known to the worker in wire. This frame is somewhat stronger than the one illustrated in Fig. 1, and gives added support to the card, since it embraces the side edges on both faces, the side bars or members of the frame being double and spaced apart to permit the card to lie between the parts thereof.

The card frame C² illustrated in Fig. 3 is similar to that shown in Fig. 1, except that the clip 6 is dispensed with, and instead the support for the lower edge 5 of the card is formed by a loop or bend 8 in the wire between the standard B² and the lower horizontal bar 2'.

In Fig. 4 I have shown a card frame C³ in which the connecting loops 26 between the 10 horizontal and the vertical side members of the frame are vertically disposed. In this arrangement the lower loops serve as the supports upon which the lower edge of the card rests, while the upper loops prevent 15 the card from being removed from the frame upwardly. This is a desirable form where it is wished to insert the cards into the frame by a lateral horizontal movement instead of vertically. It has the same advantages of supporting the card all around 20 near its edges as do the forms of invention already described. In this view the lower horizontal member of the frame is designated 2'', the upper horizontal member 3'', 25 and the parallel vertical members 4''.

Fig. 5 illustrates a form of the invention in which the standard B³ is formed of four pieces or strands of twisted wire, instead of two strands as in the constructions thus far 30 described, and in which the four strands are caused to enter into the formation of the card frame C⁴. In this arrangement one pair of strands constitute the members 9, 9, of one of the lower horizontal bars of 35 the frame, and the upright or side bars 10, 10, while the other pair of strands 11, 11, constitute the other lower horizontal bar of the frame, and the second pair of upright bars 12, 12. The two sets of upright bars 10 40 and 12 are united at their upper ends by horizontal loops 13, 13. With this arrangement two pieces of wire bent as shown and described constitute those parts of the frame which have been described.

45 In order to give added strength to a frame like that shown in Fig. 5, and to furnish support for the upper edge of the card, I connect the upper ends of one or both pairs of the uprights of the frame by horizontal 50 cross-bars. I have illustrated both sets of bars as being so connected, the uprights 10, 10 by cross-bars 14, and the uprights 12, 12 by cross-bar 15. The frame thus formed supports the card entirely around its edges 55 and both front and back. The lower support for the card is formed by the upper portion of the standard, where the coiled strands of wire forming it separate, as at 16. The loops 13 prevent the lateral movement 60 of the card, which must be placed in the frame from above and enter by a vertical movement.

In Fig. 6 I have represented another form 65 of double card frame C⁵, that is, one supporting the card all around both in front and

in rear. In this form of the invention the standard B⁴ is made up of a pair of strands which separate to form the lower horizontal member 17 of the frame. At the ends of this lower horizontal bar are downward 70 extending vertical loops 18 between which extend a second horizontal bar 19, the loops 18 serving as the supports for the lower edge of the card. Each pair of uprights 20, 20 is connected at one end,—the lower end 75 as represented in the drawings,—by a horizontal loop 21, and at their upper ends they have horizontal loops 22 uniting them with an upper cross-bar 23. A second upper cross bar 24 may be employed parallel with 80 the cross-bar 23 and united to the loops 22 by solder or brazing, as represented in the drawings. The uprights of this frame are united to the lower horizontal members by 85 soldering or brazing, as indicated at 25.

The frames herein described are intended primarily for supporting display cards, although they may be used for holding and protecting pictures and other similar articles; and I employ the term "card" herein 90 as a generic term to indicate a flat article adapted to be supported in frames such as described, whether that article be of paper, cardboard, or other material.

It will be observed that the quadrilateral 95 rectangular skeleton frame in each form of the invention has a parallel set of bars lying adjacent to the horizontal edges of the card and another set of parallel bars arranged adjacent to the vertical edges of the card; and that both bars of each set are not only parallel but are disposed so they lie upon the same side of the card, while the bars of one set are offset with reference to those of the other set and united thereto by loops so that the 100 bars which are at right angles to each other are on opposite sides of the card; and so also that the rectangular frame produced by the bars is open along one edge at least to permit the free introduction of the card edge-wise into the frame and between the bars. This arrangement affords a very complete 105 protection to the supported card, which is of advantage when the latter is made of frangible material, as it is practically impossible for the card to come into direct engagement with the support on which the rack might be placed should the latter be overturned.

What I claim is:—

1. A card rack having a quadrilateral rectangular skeleton frame adapted to support a card and protect it all around near its edges, having a set of vertical parallel bars and a set of horizontal parallel bars, the bars of each set being arranged to lie near opposite edges of the card supported, and those of one set being offset with reference to those of the other set and united thereto by loops, whereby is produced a frame open along one 120

edge at least to permit the free introduction of the card edgewise into the frame and between the bars.

2. A card rack having a quadrilateral rectangular skeleton frame adapted to support a card and protect it all around near its edges, having a set of vertical parallel bars and a set of horizontal parallel bars, the bars of each set being arranged to lie near opposite edges of the card supported, and those of one set being offset with reference to those of the other set and united thereto by horizontally disposed loops, and the frame being also provided with means for engaging with the lower edge of the card and supporting it.

3. A display rack having a standard and a card-supporting frame the standard being formed of wire and the frame of continuations of the same wire as that which constitutes the standard, and the frame being of rectangular skeleton formation having parallel horizontal bars, and parallel upright bars united at their ends respectively with the horizontal bars by horizontal loops, whereby the vertical bars are adapted to be disposed on one face of the supported card and the horizontal bars on the opposite face thereof, the frame, extending all around the card near its edges.

4. In a display card rack, a card-supporting frame formed of wire and having up-

per and lower horizontal, and upright, bars forming a rectangular frame arranged to engage with the supported card near each of its four edges, the uprights being connected with the horizontal bars by horizontal loops that serve to prevent lateral displacement of the card and also dispose the horizontal bars on one face of the card and the upright bars on the other, and the frame being provided with means engaging with the lower edge of the card to sustain it against falling.

5. In a display card rack, a card-supporting frame formed of wire and having upper and lower horizontal, and upright, bars forming a rectangular frame arranged to engage with the supported card near each of its four edges, the uprights being connected with the horizontal bars by horizontal loops that serve to prevent lateral displacement of the card and also dispose the horizontal bars on one face of the card and the upright bars on the other, and a second set of upright bars parallel with those first mentioned but disposed on the opposite face of the card, and the frame being provided with means engaging with the lower edge of the card to sustain it against falling.

WILBUR B. TIMBERLAKE.
